RAYMOND T. BISHOP, OF NEW YORK, N. Y.

EXTENSIBLE WINDOW-SCREEN.

1,130,565.

Specification of Letters Patent. Patented Mar. 2, 1915.

Application filed July 22, 1914. Serial No. 352,925.

To all whom it may concern:

Be it known that I, RAYMOND T. BISHOP, a citizen of the United States, and a resident of the city of New York, Woodhaven, borough of Queens, in the county of Queens and State of New York, have invented a new and Improved Extensible Window-Screen, of which the following is a full, clear, and exact description.

10 This invention relates to window screens and more especially to screens of the extensible type so as to be adjustable for windows of different widths.

The invention has for its general objects 15 to improve and simplify the construction of extensible window-screens so as to be more attractive in appearance, easy to adjust and so designed as to be devoid of gaps through which flies, mosquitos or other insects may enter, as the netting is of one piece with one 20 end rigidly fastened to one section of the screen and the other end being fastened on a roller mounted in the other section of the screen, whereby the netting is wound or unwound as the screen is contracted or extended.

Another object of the invention is the provision of a two-section screen in which 25 springs operate on the sections to force them apart, but which tendency is resisted by the operating means for the netting roll, such operating means including a worm wheel on the roll and a crank shaft having a worm meshing with the worm wheel, whereby the 30 roll can be turned only by the operation of the crank. In turning the crank in one direction the netting is wound on the roll and the screen contracted or made narrower by the winding of the netting on the roll, 35 whereas the reverse turning of the crank will unwind the netting and allow the springs to force the sections of the screen apart and take up the slack in the netting and maintain it taut, the netting being the 40 means for limiting the degree of expansion of the screen frame.

With such objects in view, and others which will appear as the description proceeds, the invention comprises various novel 45 features of construction and arrangement of parts which will be set forth with particularity in the following description and claims appended hereto.

In the accompanying drawing which 50 illustrates one embodiment of the invention and wherein similar characters of reference

indicate corresponding parts in all the views, Figure 1 is a perspective view of the screen; Fig. 2 is a sectional view of the screen taken parallel with the netting; Figs. 60 3, 4, and 5 are sectional views respectively on the lines 3—3, 4—4 and 5—5, Fig. 2; and Fig. 6 is a detail sectional view on an enlarged scale of the roll-operating means.

Referring to the drawing, A designates 65 the wire netting of the screen and B and C the two sections of the screen frame. The two sections of the frame are preferably made of metal of tubular form and the horizontal members 1 of the section B telescope 70 in the members 2 of the section C, and these members 1 and 2 are rigidly connected with the vertical bars 3 and 4 of the respective sections. The parts 2 and 4 are provided with slots 5 for receiving the edges of the netting A, and these edges are soldered or otherwise rigidly secured to the section C. The members 1 and 3 of the section B also have on their inner surfaces slots 6 arranged in the same plane as the slots 5 of the 75 section C, and the upper and lower edges of the netting are disposed in the slots of the members 1, while the end of the netting enters the slot 6 in the member 3 and winds on a roller 7 that extends longitudinally of 80 and is housed within the member or bar 3. The screen is expanded and contracted by the co-action of spring means and a winding device. The spring means consists of a pair of springs 8 which are arranged 85 within the upper and lower members 2 of the section C, and these springs bear against the inner ends of the members 1 of the section B, and as these springs are of the helical expansion type they tend to force the 90 screen sections apart. The winding means comprises a crank 9 or equivalent means arranged at one corner of the section B, and this crank is fastened to a horizontal shaft 10 suitably mounted in the section B, and on this shaft is a worm 11 that in its turning will rotate the worm wheel 12 fastened 95 to the roll 7. By turning the crank in one direction the roll 7 is rotated to wind up the netting A, and as a consequence the two 100 sections of the screen will be drawn together in opposition to the tension of the springs 8, but when the crank is turned in the opposite direction the roll 7 unwinds the netting therefrom and the springs 8 expand to force 105 the sections apart and maintain the netting taut. As the edges of the netting are dis-

posed within the sections of the screen no gaps are formed for the entrance of flies, mosquitos or other insects.

From the foregoing description taken in connection with the accompanying drawing, the advantages of the construction and method of operation will be readily understood by those skilled in the art to which the invention appertains, and while I have 5 described the device which I now consider to be the best embodiment thereof, I desire to have it understood that the device shown is merely illustrative and that such changes may be made when desired as are within 10 the scope of the appended claims.

Having thus described my invention, I claim as new and desire to secure by Letters Patent:

1. An extensible window screen comprising a frame made of two slidably connected sections, a netting having one end fastened to one section, a roll in the other section and to which the opposite end of the netting is fastened to wind and unwind, spring 20 means operatively related to the sections to force the same apart as the roll unwinds the netting, and gearing housed and concealed within the roll-containing section for turning the roll and forming a lock for preventing the sections from spreading apart under the tension of said spring means.

2. An extensible window screen comprising a frame made of two sections of metal tubing formed of a vertical bar and two horizontal bars, the horizontal bars of one section telescoping within those of the other, the bars having their inner surfaces provided with longitudinal slits, a netting having its upper and lower edge and one end extending into the slits of one section and 35 secured to the bars thereof, and the netting having its upper and lower edges and end disposed in the slits of the other bars of the other section and free from said bars, a roll to which the free end of the netting 40 is fastened and disposed within the vertical bar of the section in which the netting is free, a worm wheel on the roll, a worm meshing with the worm wheel for turning the roll, means for turning the worm, and 45 springs housed in the horizontal bars of the section to which the netting is rigidly secured to exert constantly a force tending to separate the sections.

In testimony whereof I have signed my 50 name to this specification in the presence of two subscribing witnesses.

RAYMOND T. BISHOP.
